UNITED STATES PATENT OFFICE

SAMUEL C. AWBREY, OF KANSAS CITY, MISSOURI, ASSIGNEE TO FLOOR ACCESSORIES COMPANY, INC., OF KANSAS CITY, MISSOURI, A CORPORATION OF MISSOURI

DESIGN FOR A THRESHOLD PLATE OR SIMILAR ARTICLE

Application filed May 8, 1930. Serial No. 35,484. Term of patent 7 years.

To all whom it may concern:

Be it known that I, SAMUEL C. AWBREY, a citizen of the United States, residing at Kansas City, in the county of Jackson and State of Missouri, have invented a new, original, and ornamental Design for a Threshold Plate, of which the following is a specification, reference being had to the accompanying drawings, forming a part thereof.

Figure 1 is a perspective view of a threshold plate showing my new design.

Fig. 2 is an inverted perspective view, and

Fig. 3 is an end view of the same.

My design comprises as an essential feature a threshold plate provided with three adjacent surface zones of substantially equal width, the central zone being smooth and each outer zone being formed to provide a series of substantially equally spaced rectangular grooves.

I claim:

The ornamental design for a threshold plate or similar article as shown and described.

SAMUEL C. AWBREY.
